UNITED STATES PATENT OFFICE.

EDWARD K. BOTTLE, OF ELMIRA, NEW YORK, ASSIGNOR TO AMERICAN SALES BOOK COMPANY, LIMITED, OF TORONTO, ONTARIO, CANADA, A CORPORATION OF CANADA.

MANIFOLDING SALES-BOOK.

1,324,333.

Specification of Letters Patent.

Patented Dec. 9, 1919.

Application filed February 23, 1918. Serial No. 218,621.

To all whom it may concern:

Be it known that I, EDWARD K. BOTTLE, a citizen of the United States, residing at Elmira, in the county of Chemung and State of New York, have invented certain new and useful Improvements in Manifolding Sales-Books, of which the following is a full, clear, and exact description, such as will enable others skilled in the art to which it appertains to make and use the same.

This invention relates to manifolding devices and with respect to its more specific features to manifolding sales books.

One object of the invention is the provision of a practical construction to facilitate the assembly and disconnection of a manifolding pad and a support therefor.

Another object is the provision of a construction to permit the production of records in triplicate, one record being a tissue sheet and to assure the efficiency of the operation of storing the triplicate beneath the unused portion of the original and duplicate pad, while maintaining the practicability and simplicity of construction of the detachable features of the device.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings forming part of this specification, wherein similar reference characters refer to similar parts throughout the several views of the drawing—

Figure 1 is a perspective view of a sales book embodying the invention; and

Fig. 2 is a cross-sectional view thereof.

In the embodiment of the invention hereinafter disclosed, there is a pad support comprising leaves 1 and 2, formed of substantial semi-rigid material, as stiff paper, cardboard, or pasteboard, said leaves being flexibly connected as by a hinge 3. Suitably fastened to one of the leaves of the pad support is a pad or pile of leaves 4, this pad being removably fastened to the support as by means of a spring clamp 5, so that other similar pads may be substituted therefor.

The leaves of the pad 4 are preferably trans-

parent, such as would be furnished by tissue sheets, and the assemblage of tissue leaves is backed by a Manila sheet 5. It will be noted that the pad 4 is connected to that side or end of the leaf 1 which is the side adjacent the hinge 3, so that the leaves of this pad may be turned upwardly, these leaves, as it were pivoting in the clamp 5.

Another pad or pile of leaves lies on the leaf 1 and is preferably composed of a plurality of superposed original leaves or sections 6 and duplicate leaves or sections 7 connected by weakened lines, as at 8, the originals being connected together as at 9, and to a sheet 10, by which latter this pad is removably attached to the support composed of the leaves 1 and 2. Preferably the attaching sheet comprises leaves 11 and 12, of flexible material, as Manila paper, the leaves being formed from a single sheet 75

adapted to fold so that the pad of original and duplicate leaves may lie therebetween. In this wise the attaching sheet serves as a flexible cover for the pad. When the pad of original and duplicate leaves is in operative position on the support, one leaf of the cover lies opposite the leaf 1 and the other leaf extends outside the periphery of the pad and lies opposite the support leaf 2, the leaves of the cover being thus, respectively, in superposed relation to those of the support, so that when the support leaves are folded to inclose the pads, a part 13 of the cover serves as a hinge for the cover and to flexibly connect the pad of original and duplicate leaves to the support, as will appear. The pad of original and duplicate leaves is attached to the leaf, as 11, of the cover along a line parallel to the line of attachment of the pad of leaves 4, 95

as at that side or end, adjacent the hinge 13, as illustrated at 9, the opposite ends of the leaves 6 and 7 being foldably joined at the weakened line 8, as already mentioned. A suitable double face carbon or other transfer sheet 14 is embodied as a leaf in the pad of original and duplicate leaves, so as to transfer impressions made on the leaf 6 to the leaves 4 and 7, when these leaves are in position for inscription with the leaf 4 between the leaves 6 and 7. Several leaves 14 may be employed at different depths in the pile. To facilitate grasping the next original sheet, the carbon sheets 14 may be recessed as at 15.

One end of the pad of original and duplicate leaves lies beside the clamp 5 within the end margin of the supporting leaf 1, so that this pad may be turned laterally on its hinge 13 and thus lifted from the leaf 1, for the reception of the inscribed tissue sheet between the pad of original and duplicate leaves and the leaf 1, where it may remain stored out of the way.

10 The leaf 12 of the Manila cover is removably attached to the support as by providing a slot in the support to receive the leaf 12. Preferably this slot is disposed longitudinally of the hinge 3 and opens adjacent thereto, as at 15. This slot may be provided by making the leaf 2 of superposed connected sheets 16 and 17 of stiff material, as pasteboard, one longitudinal edge of each of these sheets being unconnected for a portion of their length to form the slot or opening 15. Thus, in the present embodiment, in the leaf 2 is provided a pocket, accessible through the opening 15 in the wall of the pocket in which pocket the cover leaf 12 may lie and be removably retained and held, the sheets 16 and 17 being close together and preferably slightly gripping the leaf 12. The inner sheet 17 may be of considerable thickness to lessen warping and is constructed to permit access to the face of the leaf 12 while in the pocket having a recess opposite the position the leaf 12 occupies in the pocket so as to provide an opening 18 through which the face of the Manila leaf 12 may be inscribed with desired memoranda.

For the purpose of facilitating the operation of the book, a handle 19 may be provided. This handle may be a tab of strong paper fastened to the Manila leaf 11, preferably on the inner face thereof, so as to be out of the way of the stored triplicate leaves 4, and projecting beyond the periphery of the pad of original and duplicate leaves and the support 1 at the side opposite or remote from the hinged part. If desired, a portion of the supporting leaf 1, opposite which the pad of original and duplicate leaves lies, may be cut away, as at 20, to facilitate turning said pad in the operation of the device.

In operation, the edge of the Manila leaf 12 is inserted in the slot 15 so as to lie in the pocket formed by the sheets 16 and 17 and opposite the opening 18. The pad of tissue leaves is secured by the clamp 5, the backing 5^a being uppermost, the two pads being placed in alignment longitudinally. For inscription, the pad of tissue leaves is thrown back and the then upper leaf is placed between the carbon sheet and the original leaf of the other pad. The inscription is then made on the original leaf and is transferred by the carbon leaf to the tissue leaf and the duplicate leaf. The pad of original and duplicate leaves is then lifted

from the supporting leaf 1, and will turn in the cover hinge 13, and this operation will cause the inscribed tissue leaf to be withdrawn from between the original and duplicate leaves and assume position between the support and the pad of original and duplicate leaves. The inscribed original and duplicate leaves may then be detached from the pad and from each other. Any memoranda desired may be made on the Manila leaf 12 through the opening 18, which leaf is maintained in flat condition by the retaining means. The lifting and turning of the pad of original and duplicate leaves may be readily effected by grasping the tab 19, thus avoiding the necessity for grasping the pad itself. If the pad were grasped the tissue leaf lying between the original and duplicate leaves might also be grasped, and its displacement resisted. Thus there would be danger of tearing the tissue leaf. Should the tab 19 be not present, as by having been accidentally detached, the thumb may be engaged beneath the corner adjacent the cut away corner 20 to lift the book. If the book is lying on the table, one hand may grasp the tab 19 and the thumb of the other hand be placed beneath the corner at 20. Having stored the triplicate and detached the inscribed leaves, the book may be reset for the next and similar operation by inserting the next tissue leaf between the next original and the carbon sheet.

Thus by the above described construction are accomplished, among others, the objects hereinbefore referred to.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent is:

1. A manifolding sales book comprising, in combination, a support comprising hinged leaves, a flexible cover comprising hinged leaves adapted to lie in respective superposed relation to the support leaves, a pad attached to a leaf of said cover at the side adjacent said cover hinge, a pad removably attached to a leaf of said support at the side adjacent said support hinge, the other leaf of said support having a pocket in

which one leaf of said flexible cover is removably held, the wall of said pocket having an opening through which inscription may be made on the cover leaf.

- 5 2. A manifolding sales book comprising, in combination, a support comprising hinged leaves, a flexible cover comprising hinged leaves adapted to lie in respective superposed relation to the support leaves, a pad 10 attached to a leaf of said cover at the side adjacent said cover hinge, a pad removably attached to a leaf of said support at the side adjacent said support hinge, the other leaf of said support having a pocket in 15 which one leaf of said flexible cover is removably held, the wall of said pocket having an opening through which inscription may be made on the cover leaf, the leaves of said first mentioned pad comprising 20 superposed original and duplicate sections foldably joined at the end of the pad opposite its attachment to said cover, and the leaves of said second-mentioned pad being adapted to lie between the sections of the 25 leaves of the first mentioned pad.
3. A manifolding sales book comprising, in combination, a support comprising hinged leaves, a cover comprising hinged leaves adapted to lie in respective superposed relation to the support leaves, a pad attached 30 to a leaf of said cover at the side adjacent said cover hinge, a pad attached to a leaf of said support at the side adjacent said support hinge, the other leaf of said support

having a pocket in which one leaf of said cover is removably held.

4. A manifolding sales book comprising, in combination, a support comprising hinged leaves, a cover comprising hinged leaves adapted to lie in respective superposed relation to the support leaves, a pad attached to a leaf of said cover at the side adjacent said cover hinge, a pad attached to a leaf of said support at the side adjacent said support hinge, the other leaf of said support having a pocket in which one leaf of said cover is removably held, the wall of said pocket having an opening through which inscription may be made on the cover leaf.

5. A manifolding sales book comprising, in combination, a support comprising hinged leaves, a cover comprising hinged leaves adapted to lie in respective superposed relation to the support leaves, a leaf of said support having a pocket in which one leaf of said cover is removably held, a pad attached to a leaf of said support at the side adjacent said support hinge, and a pad attached to a leaf of said cover along a line parallel with the line of attachment of said other pad.

In testimony whereof I affix my signature, in the presence of two witnesses.

EDWARD K. BOTTLE.
